UNITED STATES PATENT OFFICE.

JULIAN C. SMITH, OF NEW YORK, N. Y.

DESIGN FOR A VACUUM-CARAFE.

No. 40,019.

Specification for Design.

Patented June 1, 1909.

Application filed April 2, 1909. Serial No. 487,593. Term of patent 7 years.

To all whom it may concern:

Be it known that I, JULIAN C. SMITH, a citizen of the United States, and a resident of Little Neck, Long Island, county of Queens, city and State of New York, have invented a new, original, and ornamental Design for Vacuum-Carafe, of which the following is a specification, reference being had to the accompanying drawing, forming a part thereof.

The figure is a side elevation of a vacuum carafe, showing my new design.

I claim:

The ornamental design for a vacuum carafe, as shown.

JULIAN C. SMITH.
